Patented Oct. 2, 1917.

UNITED STATES PATENT OFFICE.

CYRUS F. GROW, OF ALHAMBRA, AND JAMES M. COURTNEY, OF LOS ANGELES,
CALIFORNIA.

MULTIPLE-CYLINDER-GRINDING APPARATUS.

1,241,964.

Specification of Letters Patent.

Patented Oct. 2, 1917.

Application filed March 30, 1916. Serial No. 87,686.

To all whom it may concern:

Be it known that we, CYRUS F. GROW and JAMES M. COURTNEY, citizens of the United States, residing at Alhambra and Los Angeles, respectively, in the county of Los Angeles and State of California, have invented new and useful Improvements in Multiple-Cylinder-Grinding Apparatus, of which the following is a specification.

10 The invention is an improved automatic machine for grinding the inner surfaces of a plurality of hollow cylinders.

The machine is particularly adapted to grind automatically in one operation, the 15 inner surfaces of the cylinders of a multiple cylinder gas engine.

A desirable embodiment of the invention is illustrated in the accompanying drawings in which:

20 Figure 1 is a side elevation of the machine.

Fig. 2 is a front elevation thereof.

Fig. 3 is a horizontal sectional view of a portion of the machine taken on line x^3-x^3 25 of Fig. 2.

Fig. 4 is a vertical sectional view of a portion of the machine taken on line x^4-x^4 of Fig. 1.

Fig. 5 is a horizontal sectional view of a 30 portion of the machine taken on line x^5-x^5 of Fig. 2.

Fig. 6 is an enlarged vertical central section of the crank disk oscillating the work supporting table in a horizontal plane.

35 Fig. 7 is a sectional detail view of the gear operating the crank disk.

Fig. 8 is a sectional detail view of the gear for vertically reciprocating the work supporting table.

40 Fig. 9 is a diagrammatic view illustrating the grinding operation of one of the grinders of the machine in grinding the inner surface of a hollow cylinder.

The machine comprises a frame formed 45 with a base 1 and a pair of standards 2 located respectively at the respective ends of the base. Guides 4 are formed on the front edges of the standards 2, upon which guides are mounted by means of slides 5, a slidable 50 table 6. Said table is mounted upon the upper ends of vertical screws 7, which extend through the base 1 and on which screw pinions 8, which rest upon the base 1. Pinions 9, on shaft 10, rest above and mesh 55 with pinions 8, and pinion 11 on said shaft

meshes with pinion 12 on shaft 13 journaled at one end in bearing 14 on the base 1. The other end of the shaft 13 is coupled to the shaft of a motor 15 by means of which motor the table 6 is moved up and down 60 on the guides 4 through the medium of said shafts, pinions, and screws. Crank disks 16 are mounted within recesses in the upper surface of table 6, on the upper ends of vertical crank shafts 20, the lower ends of which 65 shafts extend through the base. The disks 16 are provided in their upper surfaces with bolt slots 21 which extend diametrically of the disks. The head ends of crank bolts 22 fit in said slots, while the shanks of said 70 bolts extend upwardly through bushings 23 in a movable table member 25 which rests upon said disks. Said movable table member is held on the bolts 22 by nuts 26 which screw on the ends of said bolts against washers resting on the top of the bushings 23. Pinions 30 are splined on shafts 20 and mesh with pinions 8, whereby motion is received from pinions 8 to rotate the shafts 20 and disks 16 to shift the movable table member 75 25 longitudinally and transversely as indicated in dotted lines in Fig. 3. The pinions 30 are confined between base bearings 31 and brackets 32 so that the shafts 20 may move longitudinally through the gears as 80 the table 6 is raised and lowered. The movable table member 25 is provided with longitudinal bolt slots 35 to receive bolts 36, which are adapted to extend through cleats 37 for engaging the end flanges 38 of the 85 cylinders 39, and nuts 40 on the ends of the bolts engage the cleats so that the cleats may grip said flanges and hold the cylinders rigidly in position on the movable table member 25. 95

On guides 45 at the upper front portion of the standards 2 is mounted, by means of slides 46, a horizontal grinder supporting bar 47. The bar may be moved to any position on the guides 45 and secured 100 in such position by bolts 48 which extend through the rear of the slides 46 and engage the rear face of said guides. Grinder heads 50 are horizontally adjustably mounted on the grinder supporting bar 47 and are 105 held in their properly adjusted position by bolts 51 fitting in a bolt slot 52 in the bar 47 and extending through ears 53 on said heads, and nuts 54 which screw on the ends of said bolts against said ears and bind the 110

- ears against said bars. Journaled in bearings 55 on the heads 50 are the vertical grinder spindles 56 on the lower ends of which are secured the grinder disks 57, preferably emery wheels, which are adapted to engage the inner surface of the engine cylinders 38. Collars 60 and 61, secured to the grinder spindles, engage respectively the upper and lower ends of the bearing 5 55 and prevent vertical movement of the spindles and grinder disks during the grinding operation of the machine. Pulleys 65 are splined on the upper portion of the spindles 56 around which pulleys extend belts 66 which extend around pulleys 67 secured on drive shaft 68 journaled in bearings 69 at the upper rear portion of the standards 2. A pulley 70 is secured on one end of the shaft 68 to which power may 10 be applied to drive the grinder disks 57 through the medium of the shaft 68, pulleys 67, belt 66, pulleys 65, and spindles 56. The position of the grinder disks 57 and the arrangement of the cylinder holding 15 cleats 37 and bolts 35 on the movable table member 25 are such that the grinder disks 57 may engage and grind the same point of the interior surface of the engine cylinders 38 as the cylinders are rotated, as shown in 20 Fig. 9, by the motion of the table member 25, whereby the interior surface of the cylinders are ground alike and to the same diameter. The diameters of the grinder disks 57 may, of course, be varied with relation to each other to grind the interior 25 surface of cylinders of different interior diameters if desirable. During the grinding operation the disks 57 may be rotated in the opposite direction to the direction of rotation of cylinders 38 as indicated by the 30 arrows in Fig. 9 which provides a highly effective and desirable grinding operation. As the grinder disks and the cylinders are 35 rotated with relation to each other as described, the cylinders are raised and lowered by the reciprocation of the table 6, whereby the grinder disks are caused to grind the interior surface of the cylinder progressively from one end to the other. 40 By securing the bolts 22 at different positions in the disk slots 21 the motion of the movable table member 25 may be varied to 45 grind cylinders of different diameters. We claim:
1. A grinding machine for grinding a plurality of integral cylinders arranged side by side, comprising a plurality of grinding elements for grinding the interior surfaces of said cylinders, a table for holding said cylinders while being ground, and means for moving said table to cause said grinding elements to grind the interior of said cylinders.
  2. A grinding machine for grinding a plurality of integral cylinders arranged side

by side, comprising a table for holding the cylinders, a plurality of grinding elements for grinding the interior surfaces of said cylinders, means for shifting said table horizontally, and means for moving said table vertically to cause said grinding elements to grind the interior of said cylinders.

3. A grinding machine, comprising a grinding element, a table, a movable table member for supporting the work, a crank 75 shaft journaled in said table, a crank element on said shaft engaging said movable table element, means for moving said table and table member toward the grinding element, and means for rotating said crank 80 shaft and crank to move said movable table member to rotate the work, said grinding element being adapted to grind the work as it is rotated and reciprocated.

4. An automatic machine for grinding the 85 interior surface of the cylinders of a multiple cylinder gas engine, comprising a slideable table, a movable table member mounted on said table, means for securing the cylinders of a multiple gas engine on said movable table member, grinding elements adapted to engage respectively the interior surfaces of said cylinders, means for actuating said grinding element, means for actuating said movable table member to rotate said 90 cylinders with relation to said grinding element, and means for moving said table and table member longitudinally with relation to said grinding element.

5. An automatic machine for grinding the 100 interior surfaces of the cylinders of a multiple cylinder gas engine, comprising a frame, a table slidably mounted on said frame, a movable table mounted on said slideable table, means for securing the cylinders of a multiple gas engine on said movable table member, a plurality of heads mounted on said frame, a spindle journaled in each of said heads, a grinding disk secured on each of said spindles adapted to engage the inner 110 surface of a cylinder of said engine, means for rotating said spindles and disks to cause said disks to grind the inner surfaces of said cylinders, means for actuating said movable table member to rotate said cylinders 115 with relation to said grinding element, and means for moving said table and table member longitudinally with relation to said grinding element.

6. An automatic machine for grinding the 120 interior surfaces of the cylinders of a multiple cylinder gas engine, comprising a slideable table, a movable table member mounted on said table, means for securing the cylinders of a multiple gas engine on said movable 125 table member, grinding elements adapted to engage respectively the interior surfaces of said cylinders, means for actuating said grinding elements, a screw journaled in said table, means for rotating said screw to move 130

said table, table member and said cylinders longitudinally with relation to said grinding element, a shaft journaled in said table, a crank on said shaft connected to said 5 movable table member, and intermeshing pinions on said screw and crank shaft whereby said shaft is rotated and said movable table member is actuated to rotate said cylinders with relation to said grinding element.

7. A grinding machine for grinding a plurality of integral cylinders arranged side by side, comprising a plurality of grinding elements for grinding the interior surfaces 15 of said cylinders, a table for holding said cylinders while being ground, means for moving said table to cause said grinding elements to grind the interior of said cylinders, and means for adjusting said grinding ele-

ments with relation to the interior of said 20 cylinders.

8. A grinding machine for grinding a plurality of integral cylinders arranged side by side, comprising a table for holding the cylinders, a plurality of grinding elements 25 for grinding the interior surfaces of said cylinders, means for shifting said table horizontally, means for moving said table vertically to cause said grinding elements to grind the interior of said cylinders, means 30 for adjusting said grinding elements with relation to the interior of said cylinders, and means for adjusting the shifting movement of said table.

In testimony whereof we have signed our 35 names to this specification.

CYRUS F. GROW,
JAS. M. COURTNEY.
